(57) **CLAIM**

The ornamental design for a carabiner multi-tool, as shown and described.

DESCRIPTION

FIG. 1 is a perspective top view of the carabiner multi-tool taken from an elevation at one end of the device;

FIG. 2 is a perspective bottom view of the carabiner multi-tool taken from an elevation at one end of the device opposite the end from which the view in FIG. 1 was taken;

FIG. 3 is a front view of the carabiner multi-tool;

FIG. 4 is a back view of the carabiner multi-tool;

FIG. 5 is a top plan of the carabiner multi-tool;

FIG. 6 is a bottom plan view of the carabiner multi-tool;

FIG. 7 is an end view of the carabiner multi-tool;

FIG. 8 is an end view of the carabiner multi-tool taken from the end opposite the end of the device from which the view of FIG. 7 was taken;

FIG. 9 is a perspective top view of the carabiner multi-tool taken from the same elevation as in FIG. 1, with the tools withdrawn from their storage compartment;

FIG. 10 is a perspective bottom view of the carabiner multi-tool taken from the same elevation as in FIG. 2, with the tools withdrawn from their storage compartment;

FIG. 11 is a front view of the carabiner multi-tool with the tools withdrawn from their storage compartment;

FIG. 12 is a back view of the carabiner multi-tool with the tools withdrawn from their storage compartment;

FIG. 13 is a top plan view of the carabiner multi-tool taken from the same direction as in FIG. 5, with the tools withdrawn from their storage compartment;

FIG. 14 is a bottom plan view of the carabiner multi-tool taken from the same direction as in FIG. 6, with the tools withdrawn from their storage compartment;

FIG. 15 is an end view of the carabiner multi-tool taken from the same direction as in FIG. 7, with the tools withdrawn from their storage compartment; and,

FIG. 16 is an end view of the carabiner multi-tool taken from the same direction as in FIG. 8, with the tools withdrawn from their storage compartment.
